UNITED STATES PATENT OFFICE.

WALDO S. KELLOGG, OF NEW YORK, N. Y., ASSIGNOR TO AUSTRAL WINDOW CO., OF NEW YORK, N. Y., A CORPORATION OF MAINE.

BALANCED WINDOW.

1,352,971.

Specification of Letters Patent. Patented Sept. 14, 1920.

Application filed May 24, 1912, Serial No. 699,414. Renewed July 21, 1920. Serial No. 398,396.

To all whom it may concern:

Be it known that I, WALDO S. KELLOGG, a citizen of the United States, residing at New York city, in the county and State of New York, have invented certain new and useful Improvements in Balanced Windows, of which the following is a full, clear, and exact description.

My invention relates to so-called balanced windows of the type described in United States Patent to E. G. Abell, No. 788182, granted April 25th, 1905, reissued November 14th, 1905, No. 12408, and Letters Patent No. 821510 to Alexander Knox, granted May 22nd, 1906, in which the upper and lower sashes are pivotally connected with the frame in such manner as to permit substantially vertical movement of the sashes and permitting a limited swinging or turning movement of each on its pivotal connection.

The chief object of my present invention is to provide a construction in which the reversal of the window can be obtained for cleaning and at the same time eliminate the guide pins and the various guide pin slots in the window frame as shown in the Knox patent. At the same time a much simpler construction is obtained which has the advantage of showing only a plain frame instead of one cut up with a multitude of slots. This advantage is of special importance when a metal frame, metal covered or so-called "kalamine" frame is employed. Here any increase in the number of slots greatly increases the cost of the window. Another feature of my new window is that when cleaning the window, an outward reversal of the upper sash is absolutely prevented. This does away with the danger of the window falling out, breaking the glass and causing possible injury to pedestrians below.

The invention which consists in the novel features of construction, arrangements of parts, and combinations of elements herein-after described and more particularly set forth in the claims, will be more clearly understood when described in connection with the accompanying drawings, wherein—

Figure 1 is a central vertical section showing the sashes opened. The sashes are also indicated in closed position by the dotted lines.

Fig. 2 is a central sectional view of Fig. 3.

Fig. 3 shows an outside elevation of the

window, the upper sash being turned at right angles preparatory to reversing for cleaning.

Figs. 4, 5 and 6 are details of the sash guide hook.

Fig. 7 is a modification of the sash guide hook preferably used on the lower sash. 60

In Fig. 1, 10 and 11 are the upper and lower sashes respectively. They are connected together by the balance arm 12. The ends of the balance arm are connected to the sashes by the pivotal connections 13 and 14. 65 15 is the jamb of the window. On the jamb at 16 is shown the pivot connecting the balance arms to the frame. The jamb 15 is shown in a sectional view in Fig. 5. Here is shown a rabbeted jamb with a longitudinal 70 groove 19. The groove is designed to receive the parting strip 20. The face of the jamb inside the groove 19 for the parting strip is set back slightly from the face of the jamb outside the groove 19. This is 75 shown at 17 and 18 in which 17 shows the plane of the jamb inside the groove and strip, and 18 the plane outside. The parting strip 20 is shown in sections 20, 20^a and 20^b. 80 20^a and 20^b may be removable.

By referring to Figs. 1 and 3 it will be seen that the groove and the general contour of the jambs are similar and continuous throughout their length. There are no grooves or slots which terminate part way. 85 Nor are there any slots running across the jamb; all run from end to end. This is of decided advantage in manufacturing, as the forming of a metal frame is a simple matter where the grooves are continuous 90 throughout. It should also be noticed that no slots are visible at any time, when the window is in either open or closed position.

In place of the studs running in grooves, as shown in the Knox and Abell patents, I 95 provide sash guide hooks 21 attached to the sash to engage on the face of the parting strip on which it moves with a rolling and sliding motion as the sash moves up and down. 100

These guide hooks are of substantially Z-iron shape, having the flanges 22 and 23 and the web 24. The flange 22 is flat and has holes drilled in it to receive the supporting screws 25. The web portion of the hook 105 is of a height substantially equal to the width of the parting strip. The flange 23 is not in an exactly parallel plane to the flange 22

but at a slight angle to it. It is also slightly curved as shown at 26. The object of this curve will be explained later.

The sash guide hooks are four in number 5 and are placed at the upper corners of the upper sash and at the lower corners of the lower sash. The flange 22 is screwed to the sash by the support screws in such a position that the web of the hook will come in 10 close proximity to the parting strip and the flange 23 will project over the parting strip. See Figs. 1, 3 and 5. The flange 23 is of such length and the hook is so placed on the sash that the tip 27 of the flange 23 extends 15 close enough to the jamb to engage the jamb 18 when a section of the parting strip is removed. This prevents the window from falling outward.

The upper sash is reversed for cleaning 20 by removing the part 20^a of the parting strip. This allows the sash guide hooks and the sash itself to pass through the parting strip and into the room where the cleaning can be carried out. When the sash is in this 25 inward position the outside of the window is inward so that it can be easily cleaned. The window is then returned to normal position and the inside cleaned.

The lower window is reversed in much 30 the same way. A portion 20^b of the parting strip can be removed and the hook retracted therethrough. Or if desired, the hook can be made with a spring connection so that it can be pulled inward and freed from the 35 parting strip.

A detail view of the spring hook is shown in a preferred form in Fig. 7. Here the parts 27, 23 and 24 are the same general form as the other hook. The flat part 29 is 40 in this case not attached to the window but is slidably mounted in a piece 31, which is attached to the sash. The end of 29 is bent up and around as shown in 30. This part 30 serves as a finger hook. A resilient connection 32 is provided. This is fastened to the hook and cooperates with the plate 31 to force the hook to the left. When it is desired to reverse the window for cleaning the window is first slightly raised. The 50 cleaner reaches out under the sash and grasping the hooks at 30 retracts them inwardly until the tip 27 of the hook clears the parting strip. The window can then be swung inward and reversed.

55 The reason for the slight curvature 26 on the guide hooks is that as the window is lowered the sash tilts away from the parting strip and the guide hook is rocked. The curvature 26 on the hook allows for this 60 rocking and at the same time keeps the guide hook in contact with the parting strip.

It is to be understood that many departures may be made from the above, which will be apparent to those skilled in the art. 65 The guide hooks may be applied to windows

of a different type from the one described, for example, in windows wherein the sashes lie in one plane when in closed position.

I claim:—

1. In a window of the kind described, the 70 combination of upper and lower sashes, a frame therefor, removable parting strips in said frame, a balancing lever pivoted to the frame and having its ends pivotally connected to the upper and lower sashes, means 75 coöperating with the parting strips to guide the sashes on a movement thereof, said parting strips adapted to be removed to reverse the windows for cleaning, said means on one of said sashes adapted to contact 80 with the outside jamb of the frame to prevent the window from reversing outwardly.

2. In a window of the kind described, the combination of upper and lower sashes, of a frame therefor provided with parting 85 strips against a face of which each of said sashes normally engages, balancing levers connected at their ends to the upper and lower sashes, and means on each sash for engaging the opposite face of the parting 90 strips to guide the sashes and permit the same to swing on their pivots and assume angular positions with respect to the frame.

3. In a window of the kind described, the combination with upper and lower sashes, 95 of a frame therefor provided with parting strips, a balancing lever pivoted to the frame and having its ends pivotally connected to the upper and lower sashes respectively, said sashes normally engaging 100 with the opposite faces of said parting strips and each of said sashes provided with guide hooks which engage the opposite face of the parting strips, whereby the upper end of the upper sash and the lower end of the lower 105 sash is guided vertically when movement is imparted to said sashes.

4. In a window of the kind described, the combination with the upper and lower sashes, of a frame therefor having parting 110 strips, each of said sashes adapted to engage with one face of the parting strips, balancing levers pivoted to the frame and having their ends pivotally connected to the upper and lower sashes respectively and 115 means on each of said sashes for engaging the other face of the parting strip to hold the ends of the sashes in the plane of the frame upon movement of the said sashes.

5. In a window of the kind described, 120 the combination with upper and lower sashes, of a frame provided with parting members, balancing levers pivoted to the frame and having their ends pivotally connected to the upper and lower sashes respectively, and guides attached to each of said sashes, said guides and sashes engaging the opposite faces of said members to guide the said sashes upon their upward and downward movement.

6. In a window of the kind described, the combination with upper and lower sashes, of a frame provided with parting members, balancing levers pivoted to the 5 frame and having their ends pivotally connected to the upper and lower sashes respectively, and guides attached to each of said sashes, said guides and sashes engaging the opposite faces of said members to 10 guide the said sashes upon their upward and downward movement, a portion of said parting members adapted to be removed to permit the reversal of the windows for cleaning.

15 7. In an improved holder for window sashes, the combination with a window frame having jambs with grooves on their inner faces, members within said grooves, upper and lower sashes for said window 20 located on opposite sides of said members, a balancing lever pivoted to the frame and having its ends pivotally connected to the upper and lower sashes, means on said sashes and engaging the faces of the members 25 on the side opposite to the side on which the particular sash is located, whereby a substantially vertical movement of the upper end of the upper sash and the lower end of the lower sash is permitted as the 30 said sashes are balanced in different positions upon the balancing arm.

8. In an improved holder for window sashes, the combination with a window frame having jambs with grooves on their 35 inner faces, removable parting strips within said grooves, upper and lower sashes for said window located on opposite sides of said parting strips, a balancing lever pivoted to the frame and having its ends pivotally connected to the upper and lower sashes, means secured to said sashes and 40 engaging the faces of the parting strips on the side opposite to the side on which the particular sash is located, whereby a substantially vertical movement is imparted to 45 the upper end of the upper sash and the lower end of the lower sash as the same are balanced in different positions upon the balancing arms, said parting strips adapted 50 to be removed whereby the sashes may be reversed for cleaning.

9. In an improved holder for window sashes, the combination with a window frame having jambs with grooves on their 55 inner faces, members within said grooves, upper and lower sashes for said window, a balancing lever pivoted to the frame and having its end pivotally connected to the upper and lower sashes, one of the faces of 60 one of said sashes adapted to contact with one of the sides or faces of said members, means on said sash adapted to engage the other sides or faces of said members whereby a substantial vertical movement is im- 65 parted to one end of the said sash, said

members adapted to be removed to permit said sash to be reversed for cleaning.

10. In an improved holder for window sashes, the combination with a window frame having jambs with grooves on their 70 inner faces, members within said grooves, upper and lower sashes, a balancing lever pivoted to the frame and having its ends pivotally connected to the upper and lower sashes, one of the faces of one of said sashes 75 adapted to contact with one of the sides or faces of said members, means on said sash adapted to engage the other sides or faces of said members, whereby a substantially vertical movement is imparted to one end of the 80 said sash, said means adapted to be retracted to permit said sash to be reversed for cleaning.

11. In a window of the kind described, the combination of upper and lower sashes, a 85 frame therefor, parting strips in said frame, a balancing lever pivoted to the frame and having its ends pivotally connected to the upper end of the upper sash and the lower end of the lower sash, means on said sashes 90 to engage the sides of the parting strip opposite the sashes and curved to compensate for the relative angular movement of said means with respect to the parting strip, said angular displacement being due to the 95 displacement of the opposite ends of the sashes upon the balancing levers, the aforesaid curved surfaces adapted to engage with the parting strips as the sashes are moved upwardly and downwardly in the frame. 100

12. In a window of the kind described, the combination of upper and lower sashes, of a frame therefor provided with parting strips against which each of said sashes normally engages and also provided with an offset portion, balancing levers connected at their ends to the upper and lower sashes, and guide means on said sashes for engaging the parting strips to guide the sashes and permit them to swing on their pivots and assume angular positions with respect to the frame, said guide means and said offset portion of the frame so constructed that the former is adapted to engage the latter to prevent the sashes from falling outwardly. 105 110 115

13. In a window of the kind described, the combination with upper and lower sashes, of a frame provided with parting members and an offset portion outside of 120 said parting members, balancing levers pivoted to the frame and having their ends pivotally connected to the upper and lower sashes respectively, and guides attached to each of said sashes, said guides and sashes adapted to normally engage said members, 125 and said guides adapted to engage the offset portion of the frame when the members are removed to prevent the sashes from falling outwardly.

14. In a window of the kind described, 130

the combination with upper and lower sashes, of a frame therefor provided with parting strips against which each of said sashes engages, balancing levers connected 5 at their ends to the upper and lower sashes, and guide means for said sashes which guides the sashes by engaging the parting strip and permits them to assume angular positions with respect to the frame, and

which maintains a contact of the sashes with 10 the parting strips in any position which the sashes may assume.

In testimony whereof I affix my signature in the presence of two subscribing witnesses.

WALDO S. KELLOGG.

Witnesses:

ALEXANDER BEGG,
MORRIS DONN FERRIS.

It is hereby certified that in Letters Patent No. 1,352,971, granted September 14, 1920, upon the application of Waldo S. Kellogg, of New York, N. Y., for an improvement in "Balanced Windows," an error appears in the printed specification requiring correction as follows: Page 3, line 58, claim 9, for the word "end" read *ends*; and that the said Letters Patent should be read with this correction therein that the same may conform to the record of the case in the Patent Office.

Signed and sealed this 19th day of October, A. D., 1920.

[SEAL.]

M. H. COULSTON,

Acting Commissioner of Patents.

Cl. 20—42.
